CLAIM

The ornamental design for a magazine holder, as shown and described.

DESCRIPTION

FIG. 1 is a front perspective view of a magazine holder showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is another perspective view, showing the status while in use.

The portions shown in broken lines illustrate environment and form no part of the claimed design.

1 Claim, 5 Drawing Sheets(56)
